UNITED STATES PATENT OFFICE.

FREDERICK K. RICKSECKER, OF WASHINGTON, DISTRICT OF COLUMBIA.

COMBINED MATCH AND CIGARETTE CASE.

Application filed September 22, 1921. Serial No. 502,458.

To all whom it may concern:

Be it known that FREDERICK K. RICKSECKER, a citizen of the United States, residing at Washington, District of Columbia, has invented certain new and useful Improvements in Combined Match and Cigarette Cases, of which the following is a specification.

This invention relates to new and useful improvements in combined match and cigarette cases, and the primary object is to provide a device of this character which is entirely water proof.

A further object of the invention resides in providing a combined device of this character which is constructed with two compartments, one for cigarettes and one for matches, but which is further constructed in such a manner as will permit of one cigarette and one match to be dispensed therefrom simultaneously by removing the cap and shaking the case.

Still another object of the invention resides in the provision of a device which is simple and durable in construction, inexpensive to manufacture, and one which is very efficient and useful in operation.

With these and other objects in view, my invention consists in the novel features of construction, the combination and arrangements of parts as will be hereinafter referred to and more particularly pointed out in the specification and claims.

In the accompanying drawings, forming a part of this application,—

Figure 1 is an elevation of the device, constructed in accordance with my invention, with parts broken away, and parts in section,

Figure 2 is a horizontal section therethrough as seen on the line 2—2, of Figure 1, and

Figure 3 is a vertical section through the device, as seen on the line 3—3, of Figure 1.

In describing the invention, I shall refer to the drawing in which similar reference characters designate corresponding parts throughout the several views and in which 1 designates a case or container formed preferably of metal but which may be constructed of any other material, impervious to water. This case is preferably made of a single blank or sheet of material and constructed to be entirely moisture or water proof.

Formed on the top of the case at one side

thereof is a tubular externally threaded neck 2, through which the cigarettes and matches are inserted and withdrawn from the case and an internally threaded cap member 3 is provided to engage and cover said neck. A water proof disc or lining 4, is provided in the cap 3 to make the device entirely water proof when carried about the person.

Arranged within the case 1 is a partition wall 5 which extends substantially to the full length of said case, the same being secured at its one end as shown at 6 to the side of the case and bent or curved as shown at 7 to be engaged with the front wall of the case at a point just below the tubular neck 2. The provision of this partition wall affords two compartments, one for matches and one for cigarettes. The compartment 75 for matches is, of course, less in depth than the compartment for cigarettes but it will be seen from the particular construction shown and described that a cigarette and a match may be dispensed from the case simultaneously upon the shaking of said case.

In filling the case cigarettes are placed in the compartment therefor by inserting them one at a time through the neck 2 and similarly matches are inserted 85 in the particular compartment therefor. When both compartments are filled, the cap member may be applied to the neck portion and an absolute water proof case for matches and cigarettes is provided. When it is desired to obtain a cigarette and a match, the cap member is removed and the case is shaken whereupon a cigarette and a match will be simultaneously dispensed therefrom. It may occur that two matches will project 95 themselves from the neck portion, but, of course, one of the same may be returned to the respective compartment therefor. When properly constructed and operated, this case will dispense one match and one cigarette 100 simultaneously.

It will be seen that this particular invention will be of great use and assistance to bathers, hunters, sailors and sportsmen. It will fill a long felt want at seashores and pleasure resorts where swimmers and sportsmen desire to be provided with dry cigarettes and matches.

The case may be carried in the pocket of the sportsmen or in the belt of the bather 110 and will be proof against moisture and water at all times. If found necessary, some

means may be provided on the outer walls of the case to attach the same to a belt or other portions of the apparel.

From the foregoing description of the construction of my improved device, the use and operation thereof will be readily understood and it will be seen that I have provided a simple, inexpensive and efficient means for carrying out the objects of the 10 invention.

While I have particularly described the elements best adapted to perform the functions set forth, it is obvious that various changes in form, proportion and the minor 15 details of construction may be resorted to, without departing from the spirit or sacrificing any of the principles of the invention.

Having thus described my invention, what I claim is:

20 1. A device of the class described, comprising a water proof case having a tubular neck formed at one end thereof, said case

being divided into compartments to respectively receive cigarettes and matches, said

compartments being so disposed with respect to said neck as to permit one match 25 and a cigarette to be simultaneously dispensed therefrom when the case is shaken and a water proof cap for said neck portion.

2. A device of the class described, comprising a water proof case having an externally threaded tubular neck member formed at one end thereof, a division wall arranged in said case to provide compartments respectively for cigarettes and matches, said 30 wall terminating at its one end immediately below said neck portion, whereby a single cigarette and a match may be dispensed simultaneously through the neck when the case is shaken and a threaded cap member 35 adapted for application to said neck portion.

In testimony whereof I affix my signature.

FREDERICK K. RICKSECKER.
